non, Ohio, a corporation of Ohio

Application March 27, 1931, Serial No. 525,706

14 Claims. (CL 230—21)

My invention relates to compressors and more particularly involves unloading arrangements therefor together with other novel features of construction.

5 My invention relates to a compressor operating on any suitable fluid medium such, for example, as a gas or gaseous medium thus generically termed in the following specification.

My invention, in a prominent phase thereof, 10 involves a step-by-step novel unloading or loading compressor arrangement, operative in either a manual or automatic sense.

My invention, in another prominent phase thereof, relates to a novel construction where- 15 by pressure relief is afforded for an unloaded side or sides of a compressor, to avoid excessive temperatures.

My invention resides in certain other novel features, characteristics and structural arrange- 20 ments.

For an understanding of my invention and for an illustration of some of the many forms thereof, reference is to be had to the accompanying drawings, in which:

25 Figure 1 is a vertical sectional view, partly in elevation, of a compressor constructed in accordance with my invention;

Fig. 2 is a vertical sectional view, partly in elevation, of a compressor constructed in accordance with my invention and arranged for 30 automatic operation;

Fig. 3 is a vertical sectional view, partly in elevation, of a manually actuatable compressor valve;

35 Fig. 4 is a vertical sectional view, partly in elevation, of an automatically actuatable compressor valve;

Fig. 5 is a vertical sectional view, partly in elevation, of a part of the control system for 40 the compressor of Fig. 2;

Fig. 6 is a side elevational view of a part of the mechanism shown in Fig. 5;

Fig. 7 is a front elevational view, partly in section of a part of the control system for the 45 compressor of Fig. 2; and

Fig. 8 is a transverse, vertical sectional view, partly in elevation, of a part of the control mechanism shown in Fig. 7.

50 Referring to Fig. 1, C represents a cylinder in which a piston P is disposed for reciprocatory movement, said piston P being connected by a piston rod to any suitable source of power, not shown. In accordance with the invention, the suction passage of the cylinder C is divided, by 55 a partition 1, into two distinct suction passages A and A1 leading, respectively, to opposite ends of said cylinder C.

Carried by the cylinder C is a structure S having a suction passage divided, by a partition 2, 60 into two distinct suction passages A2 and A3.

With the structure S properly seated on the cylinder C, the partitions 1 and 2, in effect, form a single wall isolating the suction passage A, A2 from the suction passage A1, A3. As shown in Fig. 1, the partition 2 comprises oppositely 65 extending, upper sections each having an opening 3, both of the openings 3 communicating with a common suction pipe 4. Accordingly, with the arrangement shown and described, separate passages extend from the conduit 4 to opposite, re- 70 spective ends of the cylinder C and each of these passages includes one of the openings 3.

For the closing either or both of the aforesaid passages at will, there may be utilized an arrangement as shown in Fig. 1 wherein valve 75 structures V and V1 are associated with the respective passages, said valve structures being carried by the structures. As shown, each valve structure comprises a handle 5 adapted for manual actuation, a housing 6, and a plate 7 80 adapted to seat upon a suitable interior surface of the structure S, the valve stem 8 extending through the housing 6 and connecting the plate 7 to the handle 5.

In accordance with my invention, a structure 85 S1 is suitably secured to that end of the cylinder C to the right, Fig. 1, said structure S1 comprising a passage communicating with the aforesaid cylinder passage A1 by way of a chamber 9 formed interiorly thereof, said chamber 9 90 communicating with the piston chamber of the cylinder C.

Disposed in the passage A4 is a suitable valve assembly which may be of conventional type, if desired, for permitting gas to pass from the passage A4 to the chamber 9 but preventing passage of gas in reverse direction along this path. As generally shown, this valve assembly comprises a mechanical arrangement 10 disposed on the structure S1, a stem or jack bolt 11 extending 100 therefrom into the passage A4, and a plate valve assembly generally shown at 12 for one-way control of gas as described immediately above.

Secured to one side of the structure S1 is a housing 13 carrying a chamber 14 closed to the 105 atmosphere, the interior of said chamber 14 communicating with the interior of said housing 13 and the latter adapted to communicate by a passage A5 with the aforesaid chamber 9. Extending axially through the housing 13 and passage A5 is a valve stem 15 carrying a valve plate 16 adapted to seat upon an interior surface of the structure S1 and thereby prevent communication between the passage A5 and the chamber 9, said valve stem 15, exteriorly of the housing 115 13, carrying a manually actuatable handle 17.

The cylinder C comprises a passage A6 communicating with a discharge pipe 18. In the structure S1, a passage A7 is adapted to place the passage A6 and the chamber 9 in communi- 120

cation. To the end that gas may pass from the chamber 9, through the passage A7, and thence to the passage A6, but not in reverse direction, there may be utilized a valve assembly similar 5 to that hereinbefore described for controlling the flow of gas through the passage A4 and hence given the same reference numerals.

Suitably secured to that end of the cylinder C to the left, Fig. 1, is a structure S2 having an 10 opening in which the piston rod is freely reciprocatory. Formed interiorly of the structure S2 is a chamber 19 which, by a passage A8, is adapted to communicate with the aforesaid passage A and, by a passage A9, is adapted to communicate with the aforesaid passage A6. To the 15 end that gas may flow from the passage A to the passage A8 and thence to the chamber 19, and from the latter chamber to the passage A9 and thence to the passage A6, but not in reverse direction along these respective paths, there may be associated with the respective passages A8 and A9 valve assemblies similar to the one hereinbefore described in connection with the passage A4.

25 In accordance with a phase of my invention and referring particularly to Fig. 3 which may be considered as illustrative of the valve structure V, the valve housing 6 is shown as comprising a chamber 20 having communicating therewith a passage 21 which communicates with a conduit 22 leading to a passage 23 formed in the structure S2 and communicating with the chamber 19 disposed therewithin. The valve stem 8 comprises an axial passage 8a opening at one end 30 into the aforesaid chamber 20, and at the other end into that part of the passage A2 which communicates with the inlet pipe 4 when the valve plate 7 is disposed upon its seat. To the end that gas may traverse the passage 8a of the 35 valve stem only in the direction indicated by the arrow in Fig. 3, suitable check valve mechanism is employed and, as herein shown, such mechanism comprises a valve plate 24 biased toward its seat as shown in Fig. 3 by a helical spring 25 seated on a plug 26 threaded into the valve plate 7.

40 Preferably, the valve structures V and V1 are similar, a connection similar to that just described leading from the chamber 9 of structure S1 to the hollow stem of the valve structure V1.

50 The operation of the form of my invention illustrated in Figs. 1 and 3 is as follows:

When operating under normal load conditions, 55 the valves V and V1 are open and the valve plate 16 is engaged with its seat. At this time, the compressor is symmetrically and 100% loaded. In the event that the pressure in the discharge pipe 18 rises to a sufficient extent above mean 60 pressure, the handle 17 may be actuated to remove the valve plate 16 from its seat, the valves V and V1 remaining open. The space defined by the passage A5, housing 13 and chamber 14 is thereby added to the space at the end of the cylinder C to the right. If the chamber 14 has 65 the proper dimensions the clearance thus added gives approximately 25% unloading.

70 The next step involves closure of the valve plate 16 upon its seat and closure of the valve V, the valve V1 remaining open. This restores full loading to one end of the compressor but completely unloads the other end thereby giving 75% unloading.

75 The next step involves removal of the valve plate 16 from its seat, the valve V being closed

and the valve V1 open. The clearance noted above is thereby added to the loaded side of the compressor thereby giving 75% unloading.

The final step involves closure of valve V1, the valve V remaining closed, whereby 100% unloading is obtained.

80 Accordingly, as described above, the valves V and V1, and the valve plate 16 may be manipulated as desired to obtain a desired degree of unloading, the latter being dependent, usually, upon the relation of pressure in the discharge pipe 18 to a desired pressure value.

85 The function of the conduits 22 will now be described. When the valve V is closed thereby shutting off the suction passage at the end of the cylinder C to the left, Fig. 1, any gas in the chamber 19 may pass along the conduit 22, down the passage 8a in the valve stem 8, through the check valve 24, and then into the suction passage which freely communicates with the pipe 4. When the valve V is fully open, the conduit 22 is sealed from the suction passage due to the fact that the inclined surfaces 6b of the housing 6 seal the openings passing through the section 8b of the valve stem. As 90 will be obvious, the one-way leakage path by way of conduit 22 for the valve V1 operates the same as the just described leakage path for the valve V.

95 The leakage paths constituted by the conduits 22 relate to an important feature of my invention. Thus, for example, when the end of the cylinder C to the left, Fig. 1, is unloaded by closure of the valve V, the ratio of compression is many times higher than that usually existing during those periods of operation when said cylinder end is loaded. Due to this condition, the temperature of the gas undergoing compression, while said cylinder end is unloaded, rises to an undesired high magnitude 100 unless a relief arrangement such as a conduit 22 is provided.

105 When the compressor is handling a gas other than air, it is desirable that the conduit 22 communicate with the suction passage as stated. 110 However, when the compressor is handling air, the conduits 22 may communicate directly with the atmosphere through any suitable check valve arrangement. Thus in Fig. 3 the passage 8a 115 may extend to the outer end of the valve stem rather than to the inner in which case said passage may communicate with the atmosphere 120 through a check valve.

125 The form of my invention hereinbefore described and illustrated by Figs. 1 and 3 is a 130 manually controlled system. As well, the invention may be adapted for automatic control as illustrated in connection with Figs. 2 and 4. As regards the mechanism of the two systems, the only substantial difference involves different 135 valve arrangements together with slightly different supporting arrangements therefor.

140 Thus, the cylinder C of Fig. 2 supports a structure S3 substantially the same as the corresponding structure S of Fig. 1. The structure S3 comprises a suction passage divided, by a partition 27, into the two distinct suction passages A2 and A3, each of which includes an opening 28 adapted to be closed by a valve plate and each suction passage adapted to communicate 145 with the common suction pipe 4.

150 For automatically closing either or both of the aforesaid suction passages A2 and A3 of Fig. 2 at will, there may be utilized valve structures V2 and V3 associated with the respective

passages A2 and A3. Preferably and as illustrated, these valve structures V2 and V3 are of duplicate character and hence a description of one will suffice for the other. Therefore, as regards the valve structure V3 and referring particularly to Fig. 4, said valve structure V3 is shown as comprising a housing 29 carried by the structure S3, said housing 29 having a piston 30 reciprocating therein and said piston 30 carrying a valve stem 31 terminating at one end in a valve plate 32 adapted to coact with the surface defining the opening 28. As the parts are positioned in Fig. 4, a helical spring 33 interposed between a part of the housing 29 and the piston 30 urges the latter and the valve stem 31 in an upward direction whereby the valve plate 32 tends to be lifted from the surface defining the opening 28. To overcome the spring 33 and to hold the valve plate 32 in closed position, a suitable control arrangement is utilized as hereinafter described for introducing a fluid medium under pressure into the space between the top plate of the housing 29 and the upper surface of the piston 30. To this end, said top plate may be provided with a suitable passage receiving a conduit 34 which leads to the control apparatus.

As shown in Fig. 4, the top plate of the housing 29 comprises an inner, central sleeve slidingly receiving that end of the valve stem 31 removed from the valve plate 32. Due to this arrangement, a chamber is formed with which communicates a conduit 22 similar in function to that hereinbefore described in connection with Figs. 1 and 3. The valve stem 31 comprises an axial passage as indicated at 31a, this passage communicating with the above noted chamber and with the conduit 22. Said passage 31a is adapted to be closed by a check valve 35 biased to closed position by a helical spring 36 seated upon a plug 37 carried by the valve plate 32, said plug being provided with passages as indicated at 37a whereby, when the check valve 35 is removed from its seat, air 45 may pass from the interior of valve stem 31 to the suction pipe 4.

As stated, the valve structures V2 and V3, preferably, are duplicate in character. When positioned as shown in Fig. 2, the valve plates 32 of said valve structures are adapted to close the respective openings 28 under the influence of a control medium as hereinafter described.

The structure S1 of Fig. 2 may be and preferably is a duplicate of the corresponding structure S1 of Fig. 1. In lieu, however, of the housing 13 of Fig. 1, the structure S1 of Fig. 2 carries a housing 38 in turn carrying the chamber 14. Reciprocating in the housing 38 is a piston 39 carrying a valve stem 40 having a valve plate 41 at one end thereof. The piston 39 is biased from left to right, Fig. 2, by a helical spring 42 whereby the valve plate 41 is caused to be seated and prevent passage of gas from the chamber 9 through the housing 38 and into the chamber 41. To automatically overcome the effect of the spring 42, a fluid under pressure is admitted to the interior of the housing 38, this being accomplished, in the example shown, by a conduit 43 which communicates with the interior of said housing 38 on the side of the piston 39 removed from the spring 42.

Aside from the foregoing, the arrangement of Fig. 2 may be and preferably is the same as the arrangement of Fig. 1. Hence, the description

heretofore given for Fig. 1 will suffice as a description of those parts of Fig. 2 not specifically noted above.

As stated, the arrangement of Figs. 2 and 4 is adapted for automatic control and, as one example of a suitable automatic control system, reference is to be had to Figs. 5, 6, 7 and 8 wherein R represents a conventional diaphragm regulator having a chamber 50 closed by a diaphragm 51, said chamber 50 having opening thereto a pipe 52 which leads to the discharge end of the compressor shown on Fig. 2. The diaphragm 51 actuates a weighted lever 53 to which is connected a link 54 leading to one end of a lever 55.

Pivoted to the lever 55 is a member 56 forming the control element of a conventional floating pilot valve PV having passages 57 and 58 connected in a pipe line 60 traversed by any suitable fluid under pressure. As herein shown, the line 60 is traversed by oil discharging into an oil sump 61 and being fed therefrom by a suitable pump 62.

Passages 63 and 64 of the pilot valve PV communicate, respectively, with the passages of a suitable rotary hydraulic relay HR comprising a shaft 65, the hub of which carries a blade 66 rotatably movable in a chamber 67 of said relay between stop surfaces 68 and 69. A wall 70 projects toward and engages the hub of shaft 65, the arrangement being such that the wall 70 and blade 66 divides the chamber 67 into two compartments, it being obvious that one compartment increases in size and that the other compartment decreases in size in response to rotatable movement of the blade 66.

As shown in Fig. 6, the shaft 65 carries a compensating disk 71 coactable with a member 72 slideable in a bracket 73 and pivoted to that end of the lever 55 removed from the link 54.

If it is assumed that the blade 66 is in engagement with the stop surface 69 and that the compressor of Fig. 2 is operating at zero unloading, i.e. that the valves V2 and V3 are open and the valve plate 41 closed, a condition of equilibrium exists and, so long as pressure changes do not arise, the system continues to operate with the valves in the positions stated above. However, upon occurrence of a given rise in pressure above mean pressure in the discharge line, elevation of the diaphragm 51 occurs and the pilot valve becomes operative to permit passage of oil along a path indicated by the arrows in Fig. 5. As a result, the blade 66 and shaft 65 are moved in a clockwise direction, Fig. 5, such movement of the shaft 65 causing the compensating disk 71 to partake of movement until one of the steps in said disk 71 permits downward movement of the member 56 whereby the passages through the pilot valve are closed and the blade 66 locked in the position to which moved. The position last named is the 25% unloading position of the blade 66 and shaft 65. As will be described hereinafter, such position of the shaft 65 causes the valve plate 41 to be moved from its seat, the valves V2 and V3 being open, whereby the compressor of Fig. 2 is 25% unloaded.

Thereafter, in the event that the pressure in the discharge line continues to rise sufficiently above mean pressure, the blade 66 and shaft 55 may move clockwise, Fig. 5, into positions where the unloading on the compressor of Fig. 2 is 50%, 75% and 100%, respectively, the pilot valve PV functioning as described above when the

shaft 55 arrives at successive positions to discontinue movement thereof and lock the same in those positions. As hereinafter described, in the 50% unloading position of the shaft 65, the valve plate 41 is seated, the valve V2 is closed, and the valve V3 remains open; in the 75% unloading position of said shaft 65, the valve plate 41 is again removed from its seat, the valve V2 being closed and the valve V3 open; and in the 100% unloading position, the valve V3 is closed, the valve V2 remaining closed. The rotated position of the shaft 65, then, automatically determines the per cent of unloading, said shaft taking a position automatically in response to the application of the control medium thereto.

The aforesaid shaft 65 extends through a housing 74 having a plurality of compartments or chambers Ca, Cb, Cc and Cd. With the form of my invention herein shown, although not necessarily, said housing 74 comprises four of these chambers, a sectional view of one of them being shown in Fig. 8 and this view being generally illustrative of all of said chambers.

Each compartment comprises a pair of poppet valve arrangements comprising valve stems 75 and 76 coactable, respectively, with side-by-side cams 77 and 78 rotatable with the shaft 65, the valve stems being biased into engagement with the respective cam surfaces by helical springs 79.

A conduit 80 opens into the valve chamber in which the valve stem 75 is mounted and from this chamber a passage 81 leads to the valve chamber in which the valve stem 76 is mounted. Communicating with this last named chamber is a conduit 82 and a passage 83, the latter leading to a conduit 84.

The conduit 80 may be connected to any source of fluid pressure such, for example, as to the discharge side of the compressor. The conduit 84 is for exhaust purposes and, if desired, may be connected to the atmosphere or to the suction side of the compressor.

With the form of my invention herein shown, each of the aforesaid chambers Ca, Cb, Cc and Cd are arranged as described above, the cams 77 and 78 in each chamber, however, occupying different rotated positions on the shaft 65 and being of suitable configuration. Each of said chambers has a supply conduit 80 opening thereinto, the conduit 82 of chamber Ca leading to the conduit 43 of Fig. 2, the conduit 82 of chamber Cb leading to the conduit 34 of valve V2, the conduit 82 of chamber Cc also leading to said conduit 43, and the conduit 82 of chamber Cd leading to the conduit 34 of valve V3.

In the above described 25% unloading position of the shaft 65, the cams 77 and 78 in the chamber Ca assume positions such as shown in Fig. 8 wherein the cam 77 holds the valve stem 75 in its operated or open position, the cam 78 permitting the valve stem 76 to be seated. In this, the 25% unloading position, the corresponding valve stems 75 in the chambers Cb, Cc, and Cd are seated. Accordingly, with the arrangement shown in Fig. 8, fluid under pressure passes through the conduit 80, into the valve chamber of the stem 75, along the passage 81, into the valve chamber of the stem 76, and thence along the conduit 82 to the container 43 of Fig. 2 and into the chamber to the rear of the piston 39. Passage of the fluid under pressure along the path just traced causes movement of said piston 39 from right to left, Fig. 2, whereby the valve plate 41 is unseated and the chamber 14 placed in communication

with that end of the cylinder C to the right, Fig. 2. Due to the clearance thus added, the compressor operates under approximately 25% unloading conditions since at this time the valves V2 and V3 are open.

When the shaft 65 moves into its 50% unloading position, the arrangement of the cams 77 and 78 in the chamber Ca is such that the valve stem 75 is seated and the valve stem 76 unseated. Accordingly, the passage 81 is closed and flow of fluid along the path traced above is discontinued. However, due to the unseating of the valve stem 76, a path now extends from the conduit 43 by way of conduit 82, the valve chamber of stem 76, and passage 83 to the conduit 84. Due to the described pressure condition in conduit 84, the fluid medium previously admitted to the rear side of the piston 39 freely exhausts along the path last traced to permit the valve plate 41 to be seated. Further, the cams 77 and 78 in the chamber Cb are so related to the respective stems 75 and 76 that, when the shaft 65 is in its 50% unloading position, the fluid medium under pressure passes from the source 80, through the poppet valve 100 chambers, and thence by way of conduit 82 to the conduit 34 of the valve V2 whereby the valve plate 32 of the latter is seated. Accordingly, for the 50% unloading position, the valve V2 is closed, the valve plate 41 is seated, the 105 valve V3 remaining open.

In connection with the above, it is to be noted that the cams 77 and 78 in the chamber Cb are of such configuration that the valve stem 75 remains open or operated and the valve stem 76 110 remains seated for the 75% and 100% unloading positions as well as for the 50% unloading position, said cams reversing the respective positions of the valve stems 75 and 76 only for the 0% and 25% unloading positions of the shaft 115 65.

When the shaft 65 moves to its 75% unloading position, the cams 77 and 78 in the chamber Cc cause a further application of fluid under pressure to the rear side of the piston 39 whereby 120 the valve plate 41 is again unseated. At this time, the cams in the respective chambers Ca and Cd are so related to their respective valve stems 75 that the latter are seated, the cam 77 of the chamber Cd, however, being in such position that the valve stem 75 is operated or open and the cam 78 of said chamber Cd permitting the valve stem 76 to be seated as stated above.

At the 100% unloading position of the shaft 65, the cams 77 and 78 in the chamber Cd are 130 in such position that fluid under pressure is passed along the conduit 34 of the valve V3 to cause the latter to be seated. In this position of said shaft 65, the valve V2, under the control of the cams in chamber Cb, remains closed, the valve plate 41 again being seated.

It will be obvious to one skilled in the art that the housing 74 may include but three chambers in which case there will be but one 140 chamber provided for control of the valve plate 41. Such an arrangement is practical because a set of the cams 77 and 78 may readily be given such configuration as to control the unseating of the valve plate 41 at both 25% and 75% 145 unloading.

It shall be understood that the control system hereinbefore specifically described is illustrative of but one of many forms of suitable control systems for automatically controlling a compres- 150

sor in accordance with the invention described herein.

Obviously, the arrangement comprising the conduits 22 for relieving pressure at the respective ends of the cylinder C of Fig. 2 operates substantially as hereinbefore described in connection with Figs. 1 and 3.

While the invention has been described with respect to certain particular preferred examples 10 which give satisfactory results, it will be understood by those skilled in the art after understanding the invention, that various changes and modifications may be made without departing from the spirit and scope of the invention and 15 it is intended therefore in the appended claims to cover all such changes and modifications.

What is claimed as new and desired to be secured by Letters Patent is:

1. In a compressor, a cylinder, a piston reciprocatory therein, separate shut-off valves in paths leading respectively to the opposite ends of the cylinder, a clearance chamber, and a valve interposed between said clearance chamber and one end of said cylinder.

2. In a compressor, a cylinder, a piston reciprocatory therein, means for cutting off the suction to each end of said cylinder separately, and means independent of said first named means for varying the unloading at one end of said cylinder.

3. In a compressor, a cylinder, a piston reciprocatory therein, a suction pipe, a discharge pipe, means forming separate paths communicating with said pipes and with opposite respective ends of said cylinder, valves in each path for closing the same to said suction pipe, a clearance chamber, and means for placing said chamber in communication with one end of said cylinder.

4. In a compressor, a cylinder, a piston reciprocatory therein, a suction pipe, a discharge pipe, means forming separate paths communicating with said pipes and with opposite respective ends of said cylinder, valves in each path for closing the same to said suction pipe, a clearance chamber, and a valve between one end of said cylinder and said chamber to place the latter in communication with the former, said valves being operable individually and jointly to vary the unloading of said compressor by steps.

5. In a compressor, a cylinder, a piston reciprocatory therein, a suction pipe, a discharge pipe, means forming separate paths communicating with said pipes and with opposite respective ends of said cylinder, valves in each path for closing the same to said suction pipe, a clearance chamber, a valve for opening and closing said chamber to one end of said cylinder, and means for operating said valves in definite sequence to vary the unloading of said compressor.

6. In a compressor, a cylinder, a piston reciprocatory therein, a suction pipe, a discharge pipe, means forming separate paths communicating with said pipes and with opposite respective ends of said cylinder, valves in each path for closing the same to said suction pipe, a clearance chamber, a valve for opening and closing said chamber to one end of said cylinder, and means for operating said valves first to open said clearance chamber valve, then to close said last mentioned valve and open the

first mentioned valve which is at the opposite end of the cylinder, then to re-open said clearance chamber valve, and then to close the remaining first mentioned valve.

7. In a compressor, a cylinder, a piston reciprocatory therein, a suction pipe, means for closing the path between said suction pipe and one end of said cylinder, and means for passing fluid material from said one end of said cylinder to a region of lower pressure while said path is so closed. 80

8. In a compressor, a cylinder, a piston reciprocatory therein, means for unloading one end of said cylinder, and means for relieving pressure on said one end of said cylinder during continuance of operation of said piston and while so unloaded. 85

9. In a compressor, a cylinder, a piston reciprocatory therein, a suction pipe, means forming separate paths communicating with said pipe and with opposite respective ends of said cylinder, means for closing one of said paths, and means for passing fluid material from the closed-path-end of said cylinder while so closed. 90

10. In a compressor, a cylinder, a piston reciprocatory therein, a suction pipe, means forming separate paths communicating with said pipe and with opposite respective ends of said cylinder, valve means for closing one of said paths, and means for passing fluid material from the closed-path-end of said cylinder to the region of said suction pipe beyond said valve means while so closed. 100

11. In a compressor, a cylinder, a piston reciprocatory therein, a suction pipe, means forming separate paths communicating with said pipe and with opposite respective ends of said cylinder, valve means for closing one of said paths, means for passing fluid material from the closed-path-end of said cylinder while so closed, said last named means comprising a path including the stem of said valve means, and a check valve in said path for permitting fluid flow from said cylinder and preventing flow in reverse direction. 110

12. In a compressor, a cylinder, intake and discharge passages leading to opposite ends of said cylinder, intake valves respectively associated with said intake passages, and means selectively operable for shutting off communication through each of said intake passages and intake valves to the respective ends of the cylinder during periods when the intake valves normally afford such communication. 120

13. In a compressor, a cylinder, intake and discharge passages leading to opposite ends of said cylinder, a clearance chamber, means for placing said clearance chamber in communication with one end of said cylinder, intake valves respectively associated with said intake passages, and means selectively operable for shutting off communication through each of said intake passages and intake valves to the respective ends of the cylinder during periods when the intake valves normally afford such communication. 130

14. In a compressor, a cylinder, a piston reciprocatory therein, means for closing off the suction to one end of said cylinder during the entire cycle of piston operation, and means for relieving pressure on said one end of said cylinder while the suction is thus closed off. 145

HEWITT A. GEHRES.

DISCLAIMER

1,969,507.—*Hewitt A. Gehres*, Mount Vernon, Ohio. COMPRESSOR MECHANISM.
Patent dated August 7, 1934. Disclaimer filed June 25, 1938, by the
assignee, *The Cooper-Bessemer Corporation*.

Hereby enters this disclaimer to claim 12 of said patent.
